UNITED STATES PATENT OFFICE.

CHARLES J. KLEIN, OF MILWAUKEE, WISCONSIN, ASSIGNEE TO THE CUTLER-HAMMEE
MFG. CO., OF MILWAUKEE, WISCONSIN, A CORPORATION OF WISCONSIN.

ELECTRIC SWITCH.

1,206,778.

Specification of Letters Patent. Patented Nov. 28, 1916.

Application filed June 17, 1911. Serial No. 633,711.

To all whom it may concern:

Be it known that I, CHARLES J. KLEIN, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming 10 a part of this specification.

My invention relates to electric switches.

It more especially relates to electric switches of the self-contained unit type described in my co-pending application Serial 15 No. 630,389, filed May 31st, 1911, patented August 10, 1915, No. 1,149,586.

Among the objects of my invention is to provide an improved electric switch.

A further object of my invention is to 20 provide an improved self-contained switch unit arranged to control a plurality of circuits.

Other objects and advantages of my improved construction will hereinafter appear.

25 In the accompanying drawings I have for purposes of illustration shown one form which my invention may assume. My invention is not, however, limited in its application to this form but may assume various other forms.

30 In the views of the drawing:—Figure 1 shows a perspective view of the self-contained switch mechanism. Fig. 2 shows a top plan view of the switch mechanism in position on a base. Fig. 3 shows a partial central sectional view of the switch mechanism in position in a suitable casing. Fig. 4 shows a perspective view of the switch contactor.

35 In the views of these drawings I have illustrated a self-contained switch mechanism or unit in which a push button operated snap switch mechanism is supported, guided and limited in its movement in a suitable frame comprising end members and connecting side members, which is provided with suitable terminal contacts arranged to close a circuit when the movable contact of the switch mechanism is in either of its 40 extreme positions.

45 The switch mechanism which I employ is preferably of the type described in my previously granted Patent No. 985,421 patented February 28, 1911. As illustrated in Fig. 1, this mechanism includes a recipro-

cating cam member 1 of the conformation of a double frustum positioned base to base and is provided with a central threaded shaft 2 extending through the same, which carries on its end removable push buttons 3 of a reduced diameter. A contactor 4, hereinafter described, is arranged to reciprocate in one direction when the cam member is reciprocated in an opposite direction and is arranged to make or break a circuit with a quick snap action when a garter spring 5, inclosed within the contactor, passes over the crest of the cam. The cam member is preferably supported in a pair of end members 6 provided with central perforations 7 having their edges pressed slightly outward as shown in Fig. 3 to form flanges 8. These perforations are preferably of such a diameter that while the push buttons may pass through the same, the reduced ends of the cam member may not pass through the same. Thus it is seen that these end members serve to guide and limit the movement of the operating member of the switch. The free ends of these end members are connected together by tie plates 9 which extend between the same and preferably are provided with reduced ends 10 which enter perforations near the ends of the end members and are riveted or otherwise secured to the same to form a frame. In the ends of this frame are supported insulating blocks 11 and in a preferred form these insulating blocks are provided with slots in their upper and lower surfaces to receive the reduced ends of the tie plates. These insulating blocks are provided with tapered recesses 12 arranged to permit the cam member to reciprocate through the same, and if desired insulating washers 13 may be placed around the mouths of these recesses and between the insulating members 11 and the flanges 8 on the end members. Thus it is seen that a frame is provided in which the insulating blocks or bases 14 are securely positioned and in which the operating member is guided and limited in its movement.

50 Upon the inner surfaces of the insulating members 11 terminal contacts 14 are provided. These contacts are preferably rectangular in cross section and are disposed parallel to each other on opposite sides of the recesses 12 through which the cam member passes so that the contactor 14 may en-

110

gage their outer edges with a wiping contact. In a preferred form these terminal members are fitted into suitable slots in the inner surfaces of the insulating members 11 and the edges of the members 11 adjacent the same are cut away to permit the free movement of the contactor. Each of the terminal contacts is preferably provided with a pair of shanks 15 which extend through the members 11 to the opposite side of the same. In a preferred form the terminal contacts are secured to the insulating members and terminal plates 16 are likewise secured to these insulating members by passing the ends of the shanks 15 through suitable perforations in these terminal plates and then bending over their ends as shown in Fig. 1. The terminal plates 16 are preferably fitted in suitable recesses 17 in the outer surface of the insulating members and on opposite sides of the end members 6. In a preferred form these terminal plates are provided with laterally extending arms 18 carrying binding screws 19 provided with ears 20 to facilitate the connection of the conductors to these binding screws. As illustrated in Fig. 2 a terminal plate is arranged on each side of the insulating member 6. If desired one circuit may be connected to the binding screws on one insulating member, while another circuit may be connected to the binding screws on the other member. The binding screws on one side of the insulating members however may be connected by a conducting strip 21 preferably riveted to one of the terminal plates and held in position on the other terminal plate by the binding screw. This conducting strip may be connected to the line so that when the binding screws on the opposite side of the insulating members are connected to branch circuits, a conductor connected to the terminal of the strip 21 would serve as a common conductor for either of the two circuits.

In Fig. 4 I have illustrated a perspective view of one form of contactor adapted to use in this switch. This contactor preferably comprises two sheets of metal arranged in parallel planes and spaced apart from each other. Both of these sheets are provided with central perforations of a sufficient size to permit the cam member to move through the same. One of these sheets is bent backward at its sides to form rounded portions 22 and is then bent forward substantially at right angles to its body portion to form contact surfaces 23 preferably having out-turned edges 24. In a preferred form the rounded portion 22 is cut away as at 25. The other sheet of the contactor is provided with a similarly formed rounded portion 26 with cut away portions 27 on opposite sides of the same and contact surfaces 28 similar to the contact surfaces 23

but extending in an opposite direction. When the contactor is assembled as shown in Fig. 4 the rounded portions 26 of one of the members fits within the cut away portions 25 of the other member so that pins 29 may be passed down through the rounded portions to connect the parts to form a contactor which has contact surfaces extending in opposite directions so that it may make a circuit when in either of its extreme positions. The pins 29 are preferably formed of insulating material so that the parts of the contactor are insulated from each other. Further, in order to properly insulate the garter spring 5 which is arranged to be inclosed within the contactor, an insulating strip 30 having a suitable perforation corresponding to and registering with the perforations in the contactor may be placed within the same and may be provided with extensions 31 which extend between the rounded portions 26 and the back of the contact surfaces 23 through the cut away portions 25 to insulate the two parts of the contactor and also space the same apart.

In Figs. 2 and 3 I have illustrated my improved switch unit as applied to a surface switch. As illustrated in these figures a base 32 preferably of insulating material is provided with a central recess or chamber 33 arranged to receive the unit. When mounted in this chamber one of the tie plates 9 is preferably placed flat upon the bottom of the recess as shown in Fig. 3 and secured to the same by a suitable screw 34 engaging in a threaded perforation in the tie plate, located between the insulating members 11. In a preferred form this screw has its head resting in a suitable recess in the bottom of the base 32. In order to accommodate the protruding ends of the end members 6, suitable recesses 35 are preferably provided in the bottom of the chamber 33, and in order to accommodate the flanged portions of the end members the end walls of the chamber 33 may be cut away as at 36. In order to permit the conductors to pass to the binding screws, suitable vertically extending recesses 37 may be provided in the corners of the base leading to the binding screws and in order to permit the base to be secured to a suitable support, suitable vertically extending recesses 38 may be provided between the recesses 37 on each side of the base. If desired a cover may be provided which is adapted to fit over and inclose the switch mechanism and rest upon suitable shoulders 39 around the edge of the base. This cover may be formed of insulating material if desired, or may consist of a sheet metal top or cap 40 provided with an insulating lining 41 which is fitted within the same as shown in Fig. 3. In order to permit the cover to be slipped over the push buttons when

3

the switch mechanism is in position on the base, suitable slots 42 may be provided in its opposite ends, and in order to secure the cover a suitable screw 43 may extend 5 through the cover and engage in a threaded perforation in the upper tie plate 9 between the end members 6. If desired a suitable insulating washer 44 may be carried on this screw between the cover and the tie plate.

10 When it is desired to operate the switch all that it is necessary to do is to push in one of the push buttons 3 to throw the contactor 4 to one of its extreme positions. As soon as the spring 5, housed within the 15 contactor, passes over the crest of the cam 1 the contactor is thrown with a quick snap action to one of its limits of travel against one of the sets of terminals 14. In order to make the other circuit of the switch, 20 the contactor may be thrown to its opposite position in engagement with the opposite set of terminals by simply pushing in the opposite push button. It is of course obvious that the circuit connections made to the various 25 terminals may be widely varied and that one or more circuits may be controlled as desired, or that a three wire circuit may be readily controlled by connecting a conductor to the terminal of the conducting strip 21 and providing other conductors connected in separate 30 branches of a circuit to the terminal plates 16 on the opposite sides of the insulating members 11.

By my improved construction I have provided a switch which is adapted to control a plurality of circuits if desired in which the contactor may be moved with a quick snap action from one circuit closing position to another. Further, by the provision 40 of the self-contained switch mechanism I have provided a three point switch unit which may be readily adapted to various uses and installed wherever it is desired to control a plurality of circuits and a compact 45 unitary switch mechanism readily removable and replaceable is desired. Further, the switch mechanism employed is entirely self-contained carrying complete terminal connections for the same, and is arranged 50 to limit the movement of its operating parts so that no undue strain may be exerted upon these parts. Further the switch mechanism is of a decidedly convenient construction 55 which may be readily and cheaply manufactured.

While I have in this application described one specific form which my invention may assume and one use to which it may be adapted, my invention is not limited either 60 to this form or to this particular use but may assume various other forms and be adapted to various other uses.

What I claim as new and desire to secure by Letters Patent is as follows:

65 1. In an electric switch, a snap switch

mechanism, end members for limiting and guiding the movement of its operating member, tie plates connecting the ends of said end members to form a unitary frame and a plurality of sets of terminal contacts carried 70 between said end members arranged to be engaged by said switch mechanism.

2. In an electric switch, a snap switch mechanism, end members arranged to guide and limit the movement of the operating 75 member thereof, tie plates connecting said end members to form a unitary frame, a plurality of terminal contacts located in opposite ends of said frame, and a conducting strip independent of the switch mechanism 80 connecting certain of said contacts.

3. In an electric switch, a push button snap switch mechanism, end members arranged to support and guide the operating member of the same and limit the movement 85 of the same, tie plates riveted to the ends of said end members and arranged to unite said members to form a unitary frame and terminal contacts carried by said end members.

4. In an electric switch, a push button snap switch mechanism, end members arranged to limit the movement of the operating members of the same, tie plates riveted to said end members to form a unitary frame 95 inclosing said mechanism, insulating members carried in the opposite ends of said frame and arranged to permit the reciprocation of said operating member through the same and terminal contacts carried on 100 said insulating members.

5. In an electric switch, a push button snap switch mechanism, end members arranged to limit the movement of the operating members of the same, tie plates riveted 105 to said end members to form a unitary frame inclosing said mechanism, insulating members carried in the opposite ends of said frame and arranged to permit the reciprocation of said operating member through the 110 same and terminal contacts for a plurality of circuits carried on said insulating members.

6. In combination, a push button operated snap switch mechanism, end members arranged to guide and limit the movement of the same, tie plates riveted to said end members to form a unitary frame, insulating blocks carried in the ends of said frame having tapered perforations arranged to receive the end of the operating member of said switch mechanism and means for insulating the operating member of said switch mechanism from said end members.

7. In an electric switch, a reciprocating 125 cam member of the conformation of a double frustum position base to base, a contactor arranged to move thereon, end members arranged to limit the movement of said cam member and guide the same, tie plates 130

- riveted to the ends of said end members to form a unitary frame, insulating blocks carried in the ends of said frame and provided with slots arranged to receive the ends of 5 said tie plates, terminal contacts carried on said insulating blocks on opposite sides of said cam member, said terminal contacts having extensions extending through said insulating blocks, terminal plates riveted to 10 said extensions and a conducting strip connecting a plurality of said terminal plates.
8. In an electric switch, a contactor formed of two sheets of metal having rounded interfitting ends and pins extending 15 through said ends.
9. In an electric switch, a contactor formed of two sheets of metal having rounded ends and insulating pins extending through said ends.
- 20 10. In an electric switch, a contactor formed of two sheets of metal having rounded interfitting ends and insulating pins extending through said ends.
11. In an electric switch, a sheet metal 25 contactor formed of two sheets of metal arranged in parallel planes and provided with rounded ends and oppositely extending contact surfaces extending at right angles to said sheets and connected by insulating pins extending through said rounded ends.
12. In an electric switch, a contactor including two metallic strips having central 30 registering perforations, one of said strips having rounded bent ends near its upper and lower edge and a cutaway central portion and being provided with forwardly disposed contact surfaces, the other of said strips being provided with rounded portions between its upper and lower edges and contact surfaces disposed oppositely from 40 said previously mentioned contact surfaces and means for holding the parts of said contactor together passing through said rounded portions.
13. In an electric switch, a contactor including two metallic strips having central 45 registering perforations, one of said strips having rounded bent ends near its upper and lower edge and a cutaway central portion and being provided with forwardly disposed contact surfaces, the other of said strips being provided with rounded portions between its upper and lower edges and contact surfaces disposed oppositely from 50 said previously mentioned contact surfaces, means for holding the parts of said contactor together passing through said rounded portions, and an insulating strip between said sheets having extensions passing through 55 said cutaway portion and between the rear edge of said forwardly disposed contact surfaces and the rounded portion on said second mentioned strip.

In witness whereof, I have hereunto subscribed my name in the presence of two witnesses.

CHARLES J. KLEIN.
